UNITED STATES PATENT OFFICE.

WILLIAM J. DRUGAN, OF PORTSMOUTH, OHIO.

HYDRAULIC JACK.

1,047,007.

Specification of Letters Patent. Patented Dec. 10, 1912.

Application filed February 2, 1912. Serial No. 674,931.

To all whom it may concern:

Be it known that I, WILLIAM J. DRUGAN, a citizen of the United States, residing at Portsmouth, in the county of Scioto and 5 State of Ohio, have invented new and useful Improvements in Hydraulic Jacks, of which the following is a specification.

The general object of the invention is to provide means for expediting the raising or 10 positioning of the lifting head of a hydraulic jack into contact with the object to be lifted. And to this end the invention consists in providing a hydraulic jack with pump pistons of different liquid lifting 15 capacities, the larger of which affords a means for rapidly lifting the head into contact with the object to be lifted, while the smaller which serves to operate the head to lift the object, operates to move the said 20 head more slowly.

Other objects will appear and be better understood from the following description taken in connection with the accompanying drawings, in which;

25 Figure 1 is a side elevation of the device partly in section. Fig. 2 is a vertical longitudinal section looking at right angles to Fig. 1. Fig. 3 is a detail section of the upper portion of the device showing the positions of the parts with the pistons locked. Fig. 4 is a sectional plan view of the head or reservoir with the pistons and the operating mechanism therefor removed. Fig. 5 is a detail plan of the barrel. Fig. 6 is a vertical 30 longitudinal section of the same. Figs. 7 and 8 are detail perspectives of the device for locking the outer piston to the head.

The barrel *a* is suitably connected to the base *b* and contains the lifting plunger 5 40 which is adapted to slide in the barrel and which is suitably connected at one end to the hollow head 6.

The rock shaft 7 which is journaled in the head 6 and has one end thereof adapted for 45 connection to a suitable operating handle 8, is connected so as to operate a double crank 9 which operates the pistons 10 and 11.

The liquid lifting capacity of the inner 50 piston 11 which slides in the outer piston 10, is less than the said outer piston and in the construction shown the outer piston 10 may be locked against movement whenever desired and the inner piston operated by the rock shaft 7. In the embodiment shown the 55 inner piston 11 has a groove or keeper 12 which takes one end of a latch 13 extending

through the outer piston 10. The latch 13 has an arm portion 14 pivoted between lugs 16 and which is adapted to move the latch 13 inwardly under the action of a spring 17. 60

The lock 19 for the outer piston is freely received in a longitudinal groove 20 in that portion of the outer piston which slides through the opening 21 in the bottom of the head 6 and a portion of the lock 19 extends into a recess 22 in the side of the opening 21 and thereby holds the said outer piston against turning movement. Shoulders 23 and 24 on the lock bear on the opposite faces of the body and thereby hold the lock 70 against movement with the piston. The upper end of the lock has lateral arms 25—25 which when the outer piston is moved downwardly as far as it will go, extend above an inturned portion 26 at the free end of the 75 arm portion 14 of the latch. This inturned portion 26 of the arm 14 has a recess 27 made to receive the portion of the lock protruding beyond the groove 20 so that when the portion 14 is moved inwardly by any 80 suitable means such as a set screw 28 in one side of the head 6, the inturned portion 26 will move below the arms 25—25 and, since the inward movement of the portion 14 will retract the latch 13 the inner piston 11 will 85 be free to move, while the engagement between the arms 25—25 and the inturned portion 26 will prevent the movement of the outer piston.

The cylinder 29 is detachably connected 90 in any suitable manner such as by screw threads, with the lifting plunger 5. Suitable packing 30 at the lower end of this cylinder prevents the escape of liquid around the plunger 5. The cylinder is adapted to 95 receive the head 31 of the outer piston and the portion *c* of the cylinder located beyond the screw threads thereof, is contracted so as to provide a space for the liquid which is introduced into the head through a capped 100 opening in the top thereof and passes through suitable openings in the floor of the head and into the plunger 5. The water from the space surrounding the lifting plunger is drawn through suitable openings or 105 ports 32 by the upward action of the piston and passes through openings or ports 33 into the upper compartment 34 of a block 35 screwed into or otherwise suitably connected in the lower end portion of the cylinder 29. 110 An upwardly opening check valve 36 is retained in the upper compartment of the

- block by means of a cage 37 and controls the passage from the chamber into the cylinder 29. The valve 36 closes under downward pressure thereon, whereby, the passage 5 from the upper chamber to the space surrounding the cylinder is prevented during the downward movement of either piston. Communication between the cylinder and the lower compartment 38 of the block 35 is 10 established by means of vertical openings, ports, or passages 39 which open at one end through the upper end of the block and at their lower ends communicate with lateral ports or passages 40 which extend into the lower compartment 38. Thus, during the downward movement of either piston the water is forced through the openings or passages 39 and 40 and into the lower compartment 38. 15 A check valve 41 controls communication between the lower compartment 38 and the barrel α below the lifting plunger 5. This check valve 41 is retained in the lower compartment by a cage 42 and yields or opens 20 under downward pressure such as by the water moving through the passages 39 and 40, but closes under upward pressure and is yieldingly held in its seat by a spring 43. Thus, it will be seen that when the pistons 25 are latched and the operating handle 8 oscillated, a relatively large amount of water will be drawn from the passage surrounding the lifting plunger and forced into the barrel α . This will have the effect of moving 30 the lifting plunger upwardly and more quickly than when the outer piston is locked and the inner piston operated by the operating handle 8. Thus, it will be seen that the 35 operation of adjusting the lifting head or raising it into contact with the work, may be done in a minimum of time and the operation of lifting the object be done solely by the action of the inner piston. 40 In order to cause the lifting plunger to 45 descend, I provide a release valve 44 in the form of a rod which extends through a passage 45' in the wall of the cylinder 29, the lower end of this passage being sealed by a head 45 of the rod. The upper end of the 50 rod extends through the bottom of the head 6 and the rod is adapted to be pressed upwardly by a spring 46 so that the head of the rod will normally seal the lower end of the opening through which it extends.

The valve is caused to descend by means of 55 an arm 47 on a shaft 48 arranged in the head 6 and the shaft is rocked by any suitable means such as a set screw 49 which extends through one side of the head and is adapted when screwed to move an arm 50 60 arranged in angular relation to the arm 47 and located on the shaft 48.

Although I have shown and described one embodiment of my invention it is to be understood that I am not to be limited to the 65 specific arrangement and construction of parts since various changes may be made, within the scope of the appended claims without departing from the spirit or sacrificing any of the advantages of the invention. 70

What I claim as new is:

1. In a hydraulic jack, the combination with a barrel and a liquid operated lifting plunger arranged in the barrel; of a plurality of pistons arranged one within the 75 other and adapted for lifting liquid and forcing it into the barrel, and means for locking one of said pistons to the lifting plunger for the purpose set forth.

2. In a hydraulic jack, the combination 80 with a barrel and a liquid operated lifting plunger arranged in said barrel, of a head carried by said plunger, a plurality of pistons arranged one within the other and adapted for lifting liquid and forcing it 85 into said barrel, and means in said head for locking said pistons together.

3. In a hydraulic jack, the combination with a barrel and a liquid operated lifting plunger arranged in the barrel; of a plurality of pistons adapted for lifting liquid 90 and forcing it into the barrel, and means for locking one of said pistons to the lifting plunger.

4. In a hydraulic jack, the combination 95 with a barrel and a lifting plunger having a hollow liquid holding head; of means for pumping liquid from the head into the barrel and including a plurality of pistons arranged one within the other, and means in 100 said head and supported by the outer piston for locking both of said pistons together.

In testimony whereof I affix my signature in presence of two witnesses.

WILLIAM J. DRUGAN.
